UNITED STATES PATENT OFFICE.

HENRY C. BAUGHMAN, OF BALTIMORE, MARYLAND, ASSIGNOR TO ELLA M. BAUGHMAN, OF BALTIMORE, MARYLAND.

DRYING APPARATUS.

SPECIFICATION forming part of Letters Patent No. 708,516, dated September 9, 1902.

Application filed January 9, 1902. Serial No. 89,036. (No model.)

To all whom it may concern:

Be it known that I, HENRY C. BAUGHMAN, a citizen of the United States, residing at Baltimore, in the State of Maryland, have invented certain new and useful Improvements in Drying Apparatus; and I do declare the following to be a full, clear, and exact description of the invention, such as will enable others skilled in the art to which it appertains to make and use the same.

The invention relates to drying apparatus, more particularly designed for drying plastic material—such, for instance, as whiting.

The object of the invention is to provide an apparatus of this character which shall be simple of construction, durable in use, comparatively inexpensive of production, and efficient in operation.

With this and other objects in view the invention consists of certain novel features of construction, combination, and arrangement of parts, which will be hereinafter more fully described, and particularly pointed out in the appended claims.

In the accompanying drawings, Figure 1 is a side elevation of an apparatus embodying my invention, and Fig. 2 is a vertical cross-sectional view.

The apparatus comprises a drum, preferably, but not necessarily, cylindrical in form and provided at its ends with heads 2 and 3, the diameters of which are greater than the drum and are supported to turn on rollers 5, supported in bearing-blocks 6. The side of the drum is made up of pockets 7, alternating with hot-air spaces 8. The pockets are accessible from without, while the hot-air spaces communicate with the interior of the drum, which is adapted to be supplied with hot air through a pipe 9. The drum is preferably formed of thin sheet metal capable of being bent or corrugated to produce the pockets 7 and the hot-air spaces 8, and, as shown, these pockets and hot-air spaces are arranged in annular form.

10 represents in conventional form a feed-hopper for successively charging the pockets as they rotate past the hopper.

During the rotation of the drum the material therein will become thoroughly dried and will fall out of the pockets by gravity when

the pockets arrive at the point marked *a*. This is evident for the reason that when the material to be dried is let into the pockets it is in a plastic state, and when it reaches the point marked *a*, it having become thoroughly dried, will naturally shrink and pull away from the sides of the pockets and drop therefrom.

Any suitable means may be employed for rotating the drum—such, for instance, as a worm 11, meshing with a worm-wheel 12, secured to the drum on its outer side near one end, as shown in Fig. 1.

From the foregoing description, taken in connection with the accompanying drawings, the construction, mode of operation, and advantages of the invention will be readily understood without requiring an extended explanation.

Various changes in the form, proportion, and details of construction may be made within the scope of the invention without departing from the spirit or sacrificing any of the advantages thereof.

Having thus described my invention, what I claim, and desire to secure by Letters Patent, is—

1. In a drying apparatus, the combination with a rotary drum comprising a series of alternating drying-pockets and hot-air spaces, said pockets opening to the outside air and said hot-air spaces communicating with the interior of the drum, of means arranged for supplying said pockets with material to be dried, substantially as set forth.

2. A drying apparatus comprising a drum formed on its outer side with pockets and on its inner side with hot-air spaces communicating with the interior of the drum and arranged alternately with the pockets in combination with means arranged for supplying said pockets with material to be dried, substantially as set forth.

3. A drying apparatus comprising a corrugated drum formed with alternating drying-pockets and hot-air spaces, the pockets being accessible from without and the hot-air spaces communicating with the interior of the drum, of means arranged for supplying said pockets with material to be dried substantially as set forth.

4. A drum consisting of a cylindrical corrugated body to form alternating drying-pockets and hot-air spaces, the said pockets being accessible from without and the hot-air spaces communicating with the interior of the drum, heads secured to the ends of the drum and of greater diameter than the drum, roller-bearings upon which said heads are supported and means arranged for supplying said pockets with material to be dried, and means for rotating the drum, substantially as set forth.
5. A drier comprising a cylindrical drum formed with alternating drying-pockets and hot-air spaces and provided at its ends with heads, said hot-air spaces communicating with the interior of the drum and said pock-

ets being accessible from without, substantially as set forth.

6. In a drying apparatus, a hollow rotary drum having a corrugated peripheral wall 20 forming a series of alternating drying-pockets and hot-air spaces, said pockets opening to the atmosphere and said hot-air spaces communicating with the interior of the drum, substantially as set forth. 25

In testimony whereof I have hereunto set my hand in presence of two subscribing witnesses.

H. C. BAUGHMAN.
